CLAIM

The ornamental design for a bending tool for squaring corners of wire frames, as shown and described.

DESCRIPTION

FIG. 1 is a top and right front perspective view of a bending tool for squaring corners of wire frames showing my new design;

FIG. 2 is a front elevational view;

FIG. 3 is a rear elevational view;

FIG. 4 is a left side elevational view;

FIG. 5 is a top plan view with portions of the handle broken away for ease of illustration; and

FIG. 6 is a bottom plan view with the end of the handle omitted for ease of illustration.

FIG. 1

FIG. 2

FIG. 3

FIG. 4

FIG. 6

FIG. 5
